UNITED STATES PATENT OFFICE.

EDWARD D. LEVY, OF SPRINGFIELD, MISSOURI, AND HENRY W. JACOBS, OF TOPEKA, KANSAS.

CAR-DOOR.

1,280,498.

Specification of Letters Patent.

Patented Oct. 1, 1918.

Application filed January 4, 1916. Serial No. 70,143.

To all whom it may concern:

Be it known that we, EDWARD D. LEVY and HENRY W. JACOBS, citizens of the United States, and residing at Springfield, in the 5 county of Greene and State of Missouri, and at Topeka, in the county of Shawnee and State of Kansas, respectively, have invented certain new and useful Improvements in Car-Doors, of which the following is a description, reference being had to the accompanying drawings, which form a part of our 10 specification.

Our invention relates to side doors for all house cars, such as automobile, refrigerator, 15 furniture and stock cars, being more especially adapted to box cars.

The object of our invention is to provide 20 a door for cars of the class enumerated, which will be flush with the car-sides when in closed position; at the same time providing a door which will be air-tight and water-proof and so constructed, that when locked and sealed, will be positively burglar-proof because of the impossibility to open the door 25 without first breaking the seal.

A further object of our invention is to provide a door, especially intended to be made of steel or metallic plates, which will be simple in design, strong in construction 30 and yet inexpensive to manufacture; the invention possessing a number of advantages, aside from those enumerated, inherent in the construction and which will be readily apparent from the following detailed description of the accompanying drawings, wherein:—

Figure 1 is a side elevation of the side-portion of a house car provided with our improved flush door and operating mechanism; the door being shown in closed position.

Fig. 2 is a sectional view of Fig. 1, taken on the line 2—2 of Fig. 1, looking in the direction of the arrows.

Fig. 3 is a vertical sectional view, taken on the line 3—3 of Fig. 1, looking in the direction of the arrows.

Fig. 4 is an enlarged sectional view, taken substantially on the same line as Fig. 2, 50 showing a portion of our improved door in top elevation, with the door shown in closed position.

Fig. 5 is a cross-sectional view, taken on

the line 5—5 of Fig. 1, looking in the direction of the arrows, with the door shown 55 swung outwardly preparatory to being moved to complete open position.

Fig. 6 is an enlarged cross-sectional view of the lower hinge operating mechanism and sealing hasp, taken on the line 6—6 of 60 Fig. 1, looking downwardly, showing the position of the operating mechanism or levers, in full lines, when the door is closed, and in phantom or dotted lines, when the door is swung outwardly preparatory to being moved to complete open position.

Fig. 7 is a detail view of the mechanism shown in Fig. 6, to wit, the lower hinge operating mechanism and sealing hasp being shown in elevation.

Fig. 8 is a side elevation of the mechanism shown in Fig. 7, being taken on the line 7—7 of Fig. 1, looking in the direction of the arrows.

Fig. 9 is an enlarged detail view of one of 75 the small doors arranged in the lower part of the large or main door, as shown in Fig. 1.

Fig. 10 is a vertical sectional view, taken on the line 10—10 of Fig. 9, looking in the direction of the arrows, and illustrating the 80 locking mechanism for the small door.

Fig. 11 is a detail sectional view, taken on the line 11—11 of Fig. 1, looking in the direction of the arrows, illustrating a modified form of door-rail and hanger.

In the exemplification of our invention, we have illustrated the door composed of a number of metallic sections 15, shown arranged longitudinally of the door, namely in a horizontal direction; the respective sections having their edges or sides flanged and preferably presented outwardly so as to provide the reinforcing or stiffening ribs 16; the flanges of adjacent sections being secured together in any suitable manner as, for example, by rivets and the like.

The top of the door is shown provided with suitable roller-containing hangers 17, the rollers whereof are adapted to ride along or move on the door-carrying rail. The 100 door-carrying rail is made in sections, one portion or section, to wit section 18, being pivotally mounted, while the other portion or section 19 is stationarily secured along the upper side of the car in any well known 105 manner.

The section 18 is pivotally mounted at 20, by means of any suitable hinge or bracket, to the side of the car adjacent to and above the door-opening, as more clearly shown in Fig. 1. This construction permits the free or opposite end of the rail 18 to be moved into and out of alignment with stationary rail 19; the pivotal section of the rail, in Fig. 4, being shown moved out of alignment, while in Fig. 5 it is shown swung into alignment with rail 19.

The bottom of the door is shown provided with suitable guides or brackets 21 which engage with the door-rail beneath the bottom of the door. This rail, like the door-rail above the door, is composed of a pivoted section 22 suitably hinged or pivoted at 23 to the side of the car, and a stationary section 24 secured to the car-side; the pivotal section 22 being pivoted so as to permit the free end to be swung into and out of alignment with the stationarily secured section 24, see Figs. 1 and 6.

The mechanism for operating the rail-section 18, and therefore also the door, comprises a suitable lever 25, which we will term the sealing lever, fixedly secured to the vertically disposed operating rod 26, which is held by means of suitable brackets 27, 27, more clearly shown in Fig. 6, secured to the side of the car so as to receive the upper and lower ends of rod or shaft 26, and at the same time permit the latter to rotate; it being understood, of course, that rod 26 is held against vertical movement or displacement.

The door-rails, both at top and bottom, are preferably made of Z-bars, as more clearly shown in the detail cross-sectional portion shown to the right in Fig. 4 at 19^a, although these rails may be either made of channel iron or angle iron, arranged so as to provide a horizontally disposed flat portion or leg, as, for example, shown in Figs. 11 and 6, respectively.

As the mechanism, whereby the pivoted sections of the door-rails are operatively connected with rod or shaft 26, is identical both at the top and bottom of the door, a description of the mechanism, for example at the lower part of the door, as illustrated in Fig. 6, will suffice.

The mechanism just referred to comprises an arm 28 fixedly secured to the rod 26 so as to be rotated therewith, the opposite end being pivotally secured to the link 29 which, in turn, is pivotally secured to arm 30. The arm 30 is provided with a pin 31 which is adapted to extend into the slot 32 of the pivoted rail-section.

It will be noted that the operating mechanism at the upper end of rod 26 is located above the sectional-rail 18, while the mechanism at the lower end of rod 26 is located beneath the sectional-rail 22, so that the pin

31, provided on arm 30, is presented upwardly at the lower part of the door and presented downwardly in the mechanism above the door. The pin 31 is preferably carried by arm 30 at the end which is pivotally connected to link 29; the opposite end of arm 30 being pivotally connected at 33 to the outer end of the bracket 27.

It is evident from the construction shown and described that the arm 30 will be placed under compression, that is, at right angles to the plane of the door when the door is closed, so that any pressure against the door from the inside will be on a dead center with the arm 30 and hence will not have a tendency to operate the mechanism, and therefore will not break the seal of sealing lever 25; arm 30 constituting a self-locking mechanism when the door is in closed position.

In Fig. 6 the position of the operating mechanism is shown in full lines in the position it occupies when the sectional-rail has been moved out of alignment with the door-rail 24 and the door moved to closed position; the dotted lines indicating the position of the various parts when the door is moved outwardly, preparatory to being rolled into complete open position; namely to the position where the free end of sectional-rail 22 is moved into alignment with the stationary sectional-rail 24. When lever 25 is moved to the position shown in dotted lines in Fig. 6, it will rotate shaft or rod 26, thereby swinging the pivotal point 24 of arm 28 to the point shown in dotted lines at 34^a, thereby carrying pin 31 to the point indicated at 31^a. The pin 31, extending into slot 32 of rail 22, in its movement through the arc of a circle as indicated in Fig. 6, swings the free end of rail 22 outward and into register with rail 24.

It will be understood, of course, that the rotation of rod or shaft 26 will induce the mechanism at the upper end of the rod to move in a similar manner, and therefore cause the sectional-rail 18, above the door, to also move outwardly and into register with the rail 19. With the sectional-rails 18 and 22, moved to the position indicated in dotted lines in Fig. 6, the door may be rolled along the pivoted sections 18 and 22 and onto the stationary sections 19 and 24 of the door-rails, thereby moving the door to complete open position. In order to close the door, it should be moved along the rails to the left in Fig. 1, as far as possible, namely completely onto the pivoted sections 18 and 22, when the lever 25 may be swung back to the position indicated in Fig. 1 and in full lines in Fig. 6, when the lever will pass over the staple 35, where it may be sealed in place. The movement of lever 25, as just described, rotates rod 26 and with it the levers, and links previously described, so that the latter assume the position shown in 130

full lines in Fig. 6, which will throw the pivoted rail-sections out of alinement with the stationary sections and force the door into the door-opening in the car-side and therefore flush with the car-sides.

The pivoted rails are prevented from swinging outwardly too far by means of a suitable bracket 36 secured to the car-side beneath the free end of bottom-rail 22; the bracket 36 being preferably provided with a transversely disposed slot shown at 37 in Fig. 6, which receives a pin 38 secured to the bottom-rail 22. The top rail may be provided with similar mechanism, although the limitation of movement of bottom-rail 22 will, of course, by reason of the door-connections to the rails, transmit similar limitation in movement to the upper door rail-section 18. This construction and arrangement makes the door absolutely fool-proof, and at the same time permits it to be easily operated.

In order to provide a weather-proof construction, we prefer to provide weather-strip 39, see Fig. 5, and the reverse curved flange 40 at opposite sides of the door, and a weather-strip 41 which is secured to the car-side above the door, as shown in Figs. 1 and 3; the bottom of the door being preferably made to overlap the side-sills of the car, as can more clearly be seen in Fig. 3, in such a manner as to prevent moisture from entering the car from that direction.

The top of the door is kept on the pivoted rail 18 and also on the stationary rail 19 by means of a suitable guide or upwardly presented lug 42 provided on the hangers 17. The lug 42 is shown extending to the rear of the downwardly presented surface or leg 40 of the top rails, as clearly shown in Fig. 3. This prevents the upper part of the door from moving away from the rails and therefore maintains the roller-hangers 17 in proper operative relation with the rails. The bottom of the door is prevented from jumping off of the bottom-rail by means of the brackets 21 which are preferably provided with a depending portion or lug adapted to extend to the rear of the upwardly presented portions of the bottom rails, as clearly shown in Fig. 3; the relation of the parts just described being obtained by sliding the door into position, namely onto the door-rails before the door-stop 43, see Fig. 1, is secured to the side of the car.

We have illustrated the main door provided with a small door 44 in the upper part thereof, and a door 45 in the lower part thereof; the upper small door 44 being used for the purpose of filling the car, after the main door has been closed, with such commodities as loose grain, coke, charcoal, and the like; while the lower door 45 is provided for the purpose of enabling the car to be

emptied, or partially so, of similar commodities before the main door is moved to open position.

The two small doors 44 and 45 are shown suitably hinged to the main door, so as to swing upwardly, and are locked in closed position by means of rod 46 to which is pivotally secured a sealing hasp 47, pivotally secured at 48 to the main door. Mounted on the lower door 45 is a small latch rod or member 49 provided with a spring 50 which maintains a yielding operative relation between member 49 and rod 46; latch-member 49 being adapted to have locking engagement with the bottom frame-portion about 80 door 45; the frame-portion being either provided by flanging the portion of the main door, adjacent the opening which receives door 45, as shown in Figs. 3 and 9, or in any other suitable manner.

By swinging the sealing hasp 47 about its pivotal point 48 so as to move the free end of the hasp downward, rod 46 will be pushed upwardly and still remain in locking engagement with door 44. This upward movement of rod 46, however, will permit latch-member 49 to move upwardly through the action of spring 50 and therefore out of locking engagement with the bottom frame-member or door 45, allowing door 45 to be 95 opened. Movement of the free end of hasp 47 upwardly will depress rod 46 out of locking engagement with door 44, while door 45 may still remain locked.

It is evident from the construction just described that both doors 44 and 45 may be independently opened by the movement of hasp 47 in proper direction, as previously described. As the latch-member 49 is carried entirely by door 45 and is separate from 100 the rod 46, it is evident that door 45 may be readily opened because the rod 46 will have cleared the door-frame when the latch-member 49 has been raised out of locking position.

It will be evident from the construction just described that one seal need be employed for securing the hasp 47 onto the staple 51 secured to the main door, as shown in Fig. 1. By sealing hasp 47 both small doors 44 and 45 will be held locked, and tampering or robbery of the car, without breaking the seal either of hasp 47 or of the main sealing lever 25, will be prevented.

In Fig. 11, we show the door-rail above 120 the door made in the nature of a channel, as can be seen as 19^a; the rail-section 19^a being shown secured in place by a suitable bracket 52. The hanger 17^a being substantially like hangers 17 previously described, with the 125 hanger arranged to overlap the lower flange of the rail-sections 18^a and 19^a, and the operating mechanism being similar to that shown in the other figures, a detailed description thereof need not be entered into.

We have shown and described what we believe to be the simplest and best forms of our invention, but certain details of construction may be altered without, however, departing from the spirit of our invention, and we do not wish to be confined to the exact constructions shown and described.

What we claim is:—

1. A car-door comprising an upper and a lower door-rail composed of separate sections, one section of each rail being stationarily mounted on the car-side while the other section of each rail above and below the door-opening is hingedly secured at one end thereof so as to permit the free end to swing laterally and bring it into and out of alinement with the stationarily mounted section, means for slidably mounting the door on both top and bottom rails, and operating means connected with the pivotally mounted section of both top and bottom rails, said means comprising a rotatable vertically disposed member, a pair of laterally swinging arms pivotally mounted, one adjacent the top and the other at the bottom of the door and adapted to be disposed perpendicular to the plane of the door when the latter is in closed position and thereby automatically lock the door in said position, the free ends of said arms having controlling relation with the free ends of the hinged rail-sections, said members having controlling relation with said arms.
2. A car-door adapted to lie flush with the car side when in closed position, a top and bottom rail on which the door is intended to slide, each rail comprising a stationary section and a section hingedly mounted at one end adjacent one side of the door opening so as to swing laterally into and out of alinement with the stationary section, means whereby the door is slidably mounted on the door-rails and held against displacement, operating mechanism comprising a vertically disposed rotatable shaft, an arm adjacent the top and bottom of the door and pivotally mounted at one end so as to swing laterally, the free ends of said arms having controlling relation with the free ends of the hinged rail-sections, a toggle joint connection between the vertically disposed rotatable shaft and the free end of each arm at the top and bottom of said door, and an operating lever secured to said vertically disposed rotatable shaft, said lever being adapted to be sealed in position.
3. A car door adapted to lie flush with the car-side when in closed position, a top and bottom rail on which the door is slidably mounted, one section of each rail being stationarily secured to the car-side while the other section is hingedly secured so as to have one end free to move laterally into and out of alinement with the stationary section, operating mechanism comprising a pair of

arms, one located adjacent to the top of the door while the other is located at the bottom of the door, each arm having a fixed pivotal point at one end while the other end of each arm is operatively connected to the free ends of the hinged rail-sections, a vertically disposed rotatable member, and controlling members intermediate of said vertically disposed member and the ends of said arms whereby the latter are swung into a position perpendicular to the plane of the door when the latter is in closed position, the free ends of the rail-sections moved toward the car-side and the door held in the door-opening flush with the car-side.

4. A car door adapted to lie flush with the car-side when in closed position, top and bottom door-rails each comprising a stationarily mounted section and a hingedly mounted section, the hingedly mounted sections being adapted to swing laterally into and out of alinement with the stationarily mounted sections, means whereby the door is slidably suspended on said hingedly mounted sections and controlled thereby, operating mechanism comprising a rotatable vertical shaft, laterally swinging members pivoted in proximity to the free ends of the swinging rail-sections, said members being adapted to extend perpendicular to the plane of the door when the latter is in closed position, means intermediate of said shaft and said members whereby rotation of said shaft will control said members, and a sliding connection between said members and the hingedly mounted rail-sections whereby the latter are swung into and out of alinement with the stationary rail-sections.

5. A car-door adapted to lie flush with the car-side when in closed position, top and bottom door-rails, each comprising a stationarily mounted section and a hingedly mounted section,—the hingedly mounted section of each rail being adapted to swing laterally into and out of alinement with the stationarily mounted section of the respective door-rail, means whereby the door is slidably mounted on said rail-sections and held against displacement, operating mechanism comprising a rotatable vertical shaft, laterally swinging members having fixed pivotal points and controlling relation with the free ends of the hinged rail-sections, means intermediate of said shaft and said members whereby rotation of the shaft will control said members, and means for controlling said shaft whereby rotation of the shaft to close the door will swing the free ends of said members intermediate of their fixed pivotal points and the door and into position perpendicular to the plane of the door when the latter is in closed position.

6. A car door adapted to lie flush with the car-side when in closed position, top and bottom door-rails each comprising a sta-

tionary section and a section hingedly mounted at one end so as to swing laterally into and out of alinement with the stationary section, operating mechanism comprising a vertically disposed shaft, toggle joint connections between the shaft and the hingedly mounted section of both rails whereby the latter are swung laterally when the shaft is rotated and the door thereby moved into and out of closed position, and pivoted means adapted to be disposed perpendicular to the plane of the door when the latter is in closed position whereby the hingedly mounted section and the door will be held in closed position against lateral movement.

ably mounted on the hingedly mounted section and held against displacement, operating mechanism comprising a vertically disposed rotatable shaft provided with a sealing lever whereby the shaft may be sealed against rotation, toggle connections between said shaft and the free ends of the hingedly mounted sections of both rails, and pivoted means having slot and pin connections with the free ends of the hingedly mounted rail-sections whereby contracting movement of the toggle connections will force said last mentioned means intermediate of the pivotal points thereof and the door and at right angles to the door when the latter is in closed position whereby the door will be held flush with the car-side.

7. A car door adapted to lie flush with the car-side when in closed position, top and bottom rails each comprising a stationary section and a section hingedly connected at one end so as to swing laterally into and out of alignment with the stationary section, means whereby the door is slidably mounted on the hinged sections and held against displacement, operating mechanism comprising a vertically disposed shaft rotatably mounted on the car-side and provided with an operating lever adapted to be sealed against movement, pivoted means mounted on the car-side and arranged to swing into a position disposed perpendicular to the plane of the door when the latter is in closed position, and toggle connections between said shaft and said pivoted means whereby the latter is actuated the hinged rail-sections swung laterally and the door moved into and out of the door-opening.

9. A car door adapted to lie flush with the car-side when in closed position, top and bottom door-rails, each comprising a stationary section and a section hingedly mounted at one end so as to swing laterally into and out of alinement with the stationary section, a rotatably mounted shaft 65 provided with an operating lever whereby the shaft may be sealed against movement, an arm intermediate of the shaft and the free end of the hingedly mounted section at the top and the bottom of the door, each arm being provided with a fixed pivotal point, while the free ends of the arms have slot and pin connection with the free ends of the hingedly mounted sections, and a pair of pivotally connected links intermediate 70 of opposite ends of the shaft and each arm whereby rotation of said shaft is imparted to said arms and the hingedly mounted sections of both rails moved laterally, and means whereby the door is slidably mounted on the hingedly mounted rail-sections and held against displacement. 75 80 85

8. A car door adapted to lie flush with the car-side when in closed position, top and bottom door-rails each comprising a stationary section and a hingedly mounted section adapted to move laterally into and out of alignment with the stationary section, means whereby the extent of outward movement of the hingedly mounted sections is determined, means whereby the door is slid-
